To all whom it may concern:

Be it known that I, Jack Stolkin, a citizen of the United States and a resident of the city of New York, in the county of Bronx and State of New York, have invented a new, original, and ornamental Design for a Dress, of which the following is a specification, reference being had to the accompanying drawing, forming a part thereof.

Fig. 1 is a front view of a dress showing my new design.

The characteristic feature of my design resides in the combination on the dress disclosed of the tinsel embroidery arranged on the blouse portion as shown.

I claim:

The ornamental design for a dress, substantially as shown and described.
